US00D660685S

(12) **United States Design Patent**
Bucci(10) **Patent No.:** **US D660,685 S**
(45) **Date of Patent:** **** May 29, 2012**(54) **DEVICE FOR SUPPORTING AN OBJECT**(76) Inventor: **Michael Bucci**, Glen Allen, VA (US)(**) Term: **14 Years**(21) Appl. No.: **29/403,651**(22) Filed: **Oct. 9, 2011****Related U.S. Application Data**

(60) Division of application No. 29/385,509, filed on Feb. 15, 2011, now Pat. No. Des. 649,435, which is a division of application No. 29/360,742, filed on Apr. 30, 2010, now Pat. No. Des. 635,010, which is a continuation-in-part of application No. 29/355,157, filed on Feb. 3, 2010, now Pat. No. Des. 631,729, which is a continuation of application No. 29/352,511, filed on Dec. 22, 2009, now Pat. No. Des. 613,582, which is a continuation of application No. 29/343,675, filed on Sep. 17, 2009, now Pat. No. Des. 609,077, which is a division of application No. 29/334,086, filed on Mar. 20, 2009, now Pat. No. Des. 603,245, which is a continuation-in-part of application No. 29/326,489, filed on Oct. 20, 2008, now Pat. No. Des. 602,341, which is a continuation-in-part of application No. 29/283,426, filed on Aug. 14, 2007, now Pat. No. Des. 581,251, and a continuation-in-part of application No. 29/295,012, filed on Sep. 20, 2007, now Pat. No. Des. 581,254.

Primary Examiner — Cynthia M Chin*(74) Attorney, Agent, or Firm* — Brian J. Teague**CLAIM**

I claim the ornamental design for a device for supporting an object, as shown and described.

DESCRIPTION

FIG. 1 is a perspective view of one embodiment of a device for supporting an object showing the new design;

FIG. 2 is a front elevational view thereof;

FIG. 3 is a rear elevational view thereof;

FIG. 4 is a top view thereof;

FIG. 5 is a bottom view thereof;

FIG. 6 is a perspective view of an alternative embodiment of a device for supporting an object;

FIG. 7 is a front elevational view thereof;

FIG. 8 is a rear elevational view thereof;

FIG. 9 is a left side elevational view thereof;

FIG. 10 is a right side elevational view thereof;

FIG. 11 is a top view thereof; and,

FIG. 12 is a bottom view thereof.
